STRAINER AND PACKER SETTING DEVICE

Cicero C. Brown, Houston, Tex.

Application December 19, 1936, Serial No. 116,687

10 Claims. (Cl. 166—20)

My invention relates to a means for setting a strainer and packing devices therewith in the well when the well is being finished.

In equipping the lower end of the well after the producing strata have been encountered it is sometimes necessary to set a plurality of packers at different levels above the strainer or strainers and to equip the apparatus so that the setting of the packers can be controlled. Where several packers are thus to be set it becomes difficult to introduce the assembly into position in the well without accidentally collapsing the packer or packers at some point when this is undesirable. It is to be understood that most of the packers are held against being collapsed, by frangible means such as shear pins which may be broken by contact with material in the well and allow the packer to collapse when a strain is exerted thereon. Sometimes the weight of the liner and other equipment above the packer will shear the pin at the wrong position of the assembly in the well and thus cause a material amount of damage and difficulty.

It is an object of my invention to be able to secure the setting string to the packer assembly in such manner that it is impossible to set the packers while the device is being inserted into position.

It is also an object of the invention to be able to perform such operations as washing the well, closing the back pressure valve and setting the packers in the proper sequence.

It is another object to provide a means for attachment of the setting string to the assembly which may be easily manipulated to perform the necessary operations above enumerated and to then withdraw the setting string from the setting position.

It is another object of the invention to provide a means for attachment of the setting string to the assembly, which may be easily manipulated to perform the necessary operations above enumerated and to then withdraw the setting string from the setting position.

The invention lies in the particular arrangement of the parts making up my novel construction and will be understood from the description which follows:

In the drawing, Fig. 1 is a central longitudinal section through the lower end of the well bore showing the lower end of the packer and strainer assembly with parts broken away for clearness.

Fig. 2 is a similar section showing the upper end of the assembly, it being understood that the two views together illustrate the complete device.

Figs. 3 and 4 are similar views with the parts enlarged and broken away so that the details of construction can be better understood.

Figs. 5 and 6 are broken views showing the upper and lower portions respectively with the packers in set position.

In the drawings I have shown a strainer and packer assembly which employs two packers together with the strainer. It may be understood that three or more packers may be employed in the same manner, the operation of which will be clear from the apparatus here disclosed.

In Figs. 1 and 2 the apparatus is shown as assembled in the manner in which it is to be inserted into the well. Adjacent the producing stratum 1 of the well is shown a strainer 2 of ordinary construction having at its lower end a valve housing 3 and a guide shoe 4. Above the strainer is a section of liner 11 which may be of any desired length. The upper end of the lower section of liner 11 is formed into a packer barrel 5. The type of packer here disclosed is the usual type of canvas packer in which the packer barrel 5 furnishes a support at its lower end for the lower portion of the canvas packer 6, the attachment being made through windings of wire 7. At the upper end of the packer barrel the outer surface is formed with downwardly inclined ratchet teeth. The upper end of the canvas packer is secured by windings of wire 1' to a ratchet sleeve 8. The construction of this sleeve is best seen in Fig. 3 the upper end of the ratchet sleeve having spring arms thereon with ratchet teeth formed on the inner face to engage slidably with the ratchet area of the packer barrel. It will be seen that when the ratchet sleeve is moved downwardly along the packer barrel it will automatically latch itself against movement in the reverse direction.

The construction of the packers shown at 5, 8 and 9 and 5', 8' and 9' in Figs. 1, 2, 5 and 6 is identical with that shown in Figs. 3 and 4 where in the details may be more clearly seen.

The outer face of the ratchet sleeve is connected to the setting barrel 9, the upper end of which has a connection by means of a threaded coupling 10 to a section of liner 11.

The liner 11 may be of the desired length to space the next adjacent upper packer at the proper point in the well to pack off against fluids entering the well, and it may be understood that this liner may be several hundred feet in length. The upper end of this liner is connected by a swaged nipple 12 to the lower end of a second packer barrel 13. This packer barrel and the

5 packer 6' is similar in all respects to the packer previously described. The upper end of the setting barrel 9' is connected to the lower end of a thrust sleeve 14. On the interior of the thrust sleeve is a shoulder 15 against which the setting dogs may engage to exert a downward thrust thereon. The upper end of the thrust sleeve is flared at 16 so as to allow the ready insertion of the setting string therein.

10 The swaged nipple 12 which connects the upper end of the liner with the second packer has on its interior a thrust shoulder 17 also to be engaged by the setting dogs of the inner string.

15 The setting string may ordinarily be made of a heavy tubing which is extended downwardly into the packer and strainer assembly and connected at its lower end to the lower end of the strainer and within the back pressure valve housing. With reference particularly to Fig. 3, the interior of the 20 valve housing is shown. I have a valve base 18 which forms a partition within the lower end of the housing and has a valve chamber 19 therein at the lower end of which the back pressure valve 20 is setted. This valve is held upwardly into its seat by a pressure spring 21. The upper end of the valve chamber 19 is closed by a partition except for a pair of longitudinal openings 22 therethrough. Centrally of the valve base is an axial opening to receive a pivot pin 23 formed 25 upon the valve plate 24. This pivot pin fits tightly through an opening in the valve base and has at its lower end a nut which holds the plate 24 closely against the valve base.

30 The valve plate 24 has a pair of longitudinal openings 25 therein which may be brought into registration with the openings 22 in the valve base. The plate has an upwardly extending skirt 26 thereon on the inner face of which are formed inwardly extending lugs 27 which may be engaged by the operating sleeve at the lower end of the setting string, thereby enabling the operator to rotate the valve plate 24 to open or close the openings 22 to the base.

35 Above the valve plate 24 is a stop ring 28. Said ring is screwed within the inner portion of the valve housing and has its upper end cut away on the exterior portion so as to provide an upwardly extending stop sleeve 29 spaced from the strainer. The upper end of this stop sleeve has 40 a beveled shoulder 30 against which the supporting ring 31 upon the setting string may engage.

45 The setting string 32 has at its lower end a collar 33, the lower end of which is extended outwardly and has its end face formed with an annular groove therein which forms the raceway 50 to receive anti-friction balls 34. On the upper end of the supporting ring 31 previously mentioned is a similar raceway. Said supporting ring 31 is held in properly spaced relation below the collar 33 by means of a nut or collar 35 screwed upon the outer surface of the operating sleeve 36.

55 The operating sleeve is secured at its upper end within the collar 33 and is extended downwardly 60 so as to project into the valve chamber and within the skirt 26 thereon. It has at its lower end oppositely extending lugs 37 which are adapted to engage the lugs 27 on the sleeve and thus enable the operator to rotate said sleeve.

65 70 It will be seen that the lower end of the setting string 32 is thus brought into supporting engagement with the valve housing, the supporting ring 31 resting upon the upper end of the member 28 and forming a seal therewith. The 75 supporting ring will be held stationary by the

friction with the sleeve 29 and the setting string may be rotated thereon through the anti-friction bearings between the collar 33 and the supporting ring. A downward thrust can be exerted by the setting string against the valve housing in this manner.

To lock the setting string in the assembly so that it may not be moved upwardly relative thereto I obtain a grip between the setting string and the packer and strainer assembly adjacent the upper end of said assembly. With reference particularly to Fig. 2, it will be seen that I provide a type of spear to engage the inner portion of the assembly adjacent the upper packer and it will be understood that if more than two packers are employed this spear will be adjacent the upper one of the series.

The construction of this spear can be best seen in Fig. 4. It includes a mandrel 38 which, at its lower end is screwed within a wedge collar 39. This engagement is preferably a lefthand threaded engagement so that the mandrel may be screwed upwardly within the wedge collar by a righthand rotation.

The wedge collar has an outer surface which is 25 tapered upwardly to cooperate with the pipe gripping dogs 40. Below the point of attachment of the wedge collar with the mandrel the inner diameter of the collar is increased to provide a shoulder at 41. The lower end of the collar is swaged inwardly and connected at 42 with the liner string.

The lower end of the mandrel is internally threaded and connected with a stop nut 43 which extends outwardly below the mandrel and may engage the underside of the shoulder 41 upon the wedge collar. It will be seen that this stop nut limits the upward movement of the mandrel relative to the wedge collar.

The upper end of the mandrel is connected with 40 the liner above by means of a collar 44, the walls of which are formed somewhat thicker than usual so that the lower portion thereof will form a shoulder above the upper ring 45 carrying the pipe gripping dogs 40. The outer surface of the 45 mandrel below the threaded connection with the collar 44 is formed with an annular recess on the lower side of which is an upwardly inclined shoulder 46 upon which the upper ring 45 of the pipe gripping dogs may engage and be supported. 50

The pipe gripping dogs are of ordinary construction. There are a plurality of downwardly extending arms on the collar 45, the lower ends of which are toothed with upwardly inclined teeth 47 thereon to engage the inner portion of the liner. At the lower ends of the dogs the inner surface is beveled outwardly to conform to the upper end of the wedge sleeve so that the relative downward movement of the dogs will cause them to engage the wedge sleeve and be forced 60 outwardly against the pipe.

At a convenient point below the packer assembly I provide upon the setting string a set of packer setting dogs 48. These dogs are not of novel construction. Each dog has a lower shoulder 49 which extends outwardly from its engagement with the section of liner upon which it is mounted and is adapted to engage with the shoulders above the packers so as to set the packers when this operation is desired. The dogs 70 are provided with lower lugs 50 and upper lugs 51, both of which engage beneath shoulders on the liner section to limit the outward movement of the dogs. The lower end of each dog is provided with a recess to receive a compression spring 75

52 which tends to force the lower ends of the dogs outwardly.

In the operation of my device the assembly is connected up, as shown in Figs. 1 and 2, with the packers collapsed and the lower end of the setting string resting upon the upper end of the back pressure valve housing, as shown in Fig. 3. The spear is expanded, as shown particularly in Fig. 2, to engage the inner portion of the packer assembly and prevent relative upward movement of the setting string in the said assembly. It will be therefore seen that the packer and strainer assembly is held against downward movement of the setting string relative thereto at the lower end 15 and against relative upward movement by the engagement of the spear with the interior of the assembly. It will thus be possible to exert a downward thrust upon the strainer and packers to move them into the bottom of the hole. It 20 will be noted that the well is shown as equipped with a casing which extends downwardly to a point adjacent the producing formation. Below this the assembly projects into the open hole. I desire to set the lower packer 6 to cut off from 25 the producing formation the stratum 54. When the well is to be brought in the flushing fluid is pumped downwardly through the setting string and through the lower end of the same by way of the back pressure valve. The fluid will then 30 ascend outside of the strainer and the packers upwardly to the surface, washing the lower end of the well. When this has been completed I close the back pressure valve.

In order to be able to rotate the setting string 35 to perform this operation I release the spear from the packer assembly. To do this I rotate the setting string in a righthand direction and screw the mandrel 38 upwardly from its position shown in Fig. 2 within the wedge collar. This raises the pipe gripping dogs 40 upwardly away from the tapered surface into the position shown in Fig. 4 with the dogs in released position.

Valve 25 is closed by rotating the setting string upon the bearing formed by the balls 34 to move 45 the valve plate 24 and bring the openings 25 out of registration with the openings 22. This will seal the lower end of the well against the flow of fluid in either direction.

I then raise the setting string somewhat and 50 wash the interior of the strainer and then set the packers. It is obvious, however, that the packers may be set before the inner portion of the strainer assembly is washed, when desired.

In order to set the packers I raise the setting 55 string until the setting dogs 48 are raised from their position shown in Fig. 2 to engage above the shoulder 17. I then lower the setting string to exert pressure upon the shoulder 17 and move the section of liner and the setting barrel 9 downwardly to collapse the packer 6. This is done by shearing the shear pin 55. This allows the ratchet sleeve 8 to be moved downwardly along the packer barrel and collapse the packer at this point. I then raise the setting string to bring 60 the setting dogs above the shoulder 15 adjacent the upper packer and again the setting string is used to exert a thrust downwardly on the setting barrel 9 to shear the pin 55 and collapse the packer 6.

The advantage of this construction lies in the 70 ability of the operator while he is going into the well and manipulating the device into proper position to prevent any downward force to be applied to the packers before it is necessary to set them. The engagement of the spear at a point

adjacent the upper end of the assembly holds the intermediate portion of the assembly against movement in either direction for the lower end of the setting string has a strong supporting engagement with the upper end of the valve housing 5 3 and the upper end of the assembly is held by the spear, the intermediate portion of the assembly being held spaced properly by this engagement. It is thus impossible to set the packers or to accidentally loosen the shear pins before it is 10 desired to perform the setting operation. Furthermore, when the packers are set it is possible to exert a thrust upon the setting barrel in each packer separately so that it may be assured that each packer is properly collapsed into sealing 15 position. In other devices where a plurality of packers are to be employed the setting operation is performed by a thrust against the upper one of the packers. This operation is unreliable, however, because if the upper packer is set first it 20 then becomes impossible to set any of the packers below. My device is, therefore, reliable in its operation and makes it possible to properly equip the lower end of the well without danger of error.

What is claimed as new is:

1. In combination, a strainer and packer assembly including a strainer, a valve housing thereon, a liner above said strainer and a plurality of packers spaced apart on said liner above said strainer; and means to set said assembly including a string of tubing, means thereon adjacent the lower end thereof to seat rotatably within said valve housing, and means on said string adjacent the upper end of said assembly to engage said setting string with said assembly to prevent relative upward movement of said string in said assembly. 25

2. In combination, a strainer and packer assembly including a strainer, a valve housing thereon, a liner above said strainer and a plurality of packers spaced apart on said liner above said strainer; and means to set said assembly including a string of tubing, means on said string adjacent the lower end thereof to seat rotatably within said valve housing, and a spear on said setting string adjacent the upper end of said assembly to engage said assembly and prevent relative downward movement of said assembly, said engagement being releasable by rotation of said string. 40

3. In combination, a strainer and packer assembly including a strainer, a valve housing thereon, a liner above said strainer and a plurality of packers spaced apart on said liner above said strainer; and means to set said assembly including a string of tubing, means on said string adjacent the lower end thereof to seat rotatably within said valve housing, and a spear on said string engaging said assembly adjacent the uppermost of said packers to prevent upward movement of said string in said assembly. 50

4. A packer and strainer assembly including a plurality of spaced packers above said strainer, in combination with a setting string, a rotatable support for said string at the lower end of said strainer, and means on said string positioned to engage said assembly adjacent the upper end thereof and support the weight of said assembly while said assembly is being introduced into the well. 60

5. A packer and strainer assembly including a plurality of spaced packers above said strainer, in combination with a setting string, a rotatable support for said string at the lower end of said strainer, and means on said string positioned to 70 75

engage said assembly adjacent the upper end thereof and support the weight of said assembly while said assembly is being introduced into the well, said means being releaseable by rotation of 5 said string.

6. A liner, a plurality of packers spaced apart upon said liner, frangible means on each packer to resist longitudinal collapsing of said packers, a setting string adapted to extend downwardly through said liner and engage therewith, means on said string to exert a downward thrust on said liner adjacent the lower end thereof, and a spear 10 on said string adjacent the uppermost of said packers to engage said liner and hold the packers spaced from the lower end of said string and to prevent collapsing of said packers between said spear and said liner engaging means.

7. A liner, a plurality of packers spaced apart upon said liner, frangible means to resist longitudinal collapsing of said packers, a setting string adapted to extend downwardly through said liner, means on said string to engage with and exert a downward thrust on said liner adjacent the lower end thereof, and a spear on said string 25 adjacent the uppermost of said packers to engage said uppermost packer to hold the upper end of said liner spaced from the lower end thereof and to prevent collapsing of said packers, said spear being releasable from packers 30 engaging position, and means on said string to engage separately above each of said packers and collapse the same.

8. A well assembly including a strainer, a liner and a plurality of superposed packers above said strainer; in combination with a setting string, means on said string to engage and exert a downward thrust on the lower end of said assembly, and supporting means on said string to engage said assembly adjacent the upper end thereof and sustain the weight of said assembly. 5

9. A well assembly including a strainer, a liner and a plurality of superposed packers above said strainer; in combination with a setting string, means on said string to engage and exert a downward thrust on the lower end of said assembly, and supporting means on said string to engage said assembly adjacent the upper end thereof and sustain the weight of said assembly, 10 said supporting means being releasable, and means on said string to separately engage said packers to collapse the same successively in upward sequence. 15

10. A packer and strainer assembly including a liner, a plurality of spaced packers thereon, a strainer on said liner and a back pressure valve housing on said strainer, a rotatable valve in said housing, in combination with a setting 25 string, a thrust support for said string adjacent the upper end of said housing, means on said string to engage and move said rotatable valve, a spear on said string to engage and support said assembly, said spear being releasable by rotation, 30 and means to engage and expand said packers.

CICERO C. BROWN.
